CIGAR TIP

Theodore Eron, Demarest, N.J., assignor to American Brands, Inc., New York, N.Y.

Filed July 30, 1973, Ser. No. 384,119

Term of patent 14 years

Int. Cl. D27—02

U.S. Cl. D27—7

FIG. 3

FIG. 2

FIG. 4

FIG. 5

FIG. 6

FIG. 1 is a perspective view of a cigar tip showing my new design;

FIG. 2 is a right end elevational view thereof;

FIG. 3 is a top plan view thereof;

FIG. 4 is a side elevational view thereof;

FIG. 5 is a bottom plan view thereof; and

FIG. 6 is a left end sectional view through line 6—6 in FIG. 4.

I claim:

The ornamental design for a cigar tip, substantially as shown and described.
